UNITED STATES PATENT OFFICE.

LOUIS J. RUSSELL, OF RICHMOND HILL, NEW YORK, ASSIGNOR TO NEWSKIN COMPANY, OF BROOKLYN, NEW YORK, A CORPORATION OF NEW YORK.

CLOSURE DEVICE FOR CONTAINERS.

Application filed December 11, 1925. Serial No. 74,786.

This invention relates to closure devices for containers, and particularly to that class of closures which includes a dipper for removing a portion of the contents of the container.

At present it is common to mount a rigid dipper, such as a glass rod or dropper, in a resilient closure such, for instance, as a cork stopper, so that when the stopper is in place in the container the dipper will project into the contents of the container, and when the stopper is removed the dipper will be removed with it and will withdraw a portion of the contents from the container.

In order to effectively close the container, however, it is necessary to force the stopper into the mouth of the container until the stopper becomes compressed to such an extent that the reactive force developed will maintain the stopper in place because of the friction between the stopper and the contacting portion of the container.

Inasmuch as the stopper not only acts as a closure for the container, but also as a handle for the dipper, it is necessary to extract the stopper from the container in such a manner that it will not be destroyed or materially weakened. Because of this fact it is impracticable to use stopper extracting devices which penetrate the stopper, and it is, therefore, the usual practice to extract the stopper by applying a transverse as well as a longitudinal force to the stopper, developing a rocking motion as well as a withdrawing motion. This rocking motion oftentimes results in the dislocation or, when the dipper is of fragile material, in the breaking of the dipper which the stopper carries.

The present invention has for its object to so mount the dipper within the stopper that the usual rocking and withdrawing actions will not result in the dislocation or fracture of the dipper, with the result that the stopper and rod will maintain their original assembly throughout use.

I have illustrated one form of the invention in the drawings, in which

Figure 1 is a longitudinal, sectional view showing the stopper in place in a bottle;

Figure 2 is a transverse, sectional view on the line 2-2 of Figure 1; and

Figures 3 and 4 are sectional views of modifications of the device.

For illustrative purposes I have shown the application of the invention to a bottle stop-

per, but I do not wish to be limited to this use, for it is obvious that the invention may be used in connection with other types of containers.

The embodiment of the invention illustrated includes a compressible stopper 1 which has sufficient resiliency so that when it is forced into the mouth of the container it will be held in such position by the friction developed between the stopper and the contacting portion of the container.

While cork is an admirable material for the stopper, it is obvious that other materials possess the same qualities and the invention is, therefore, not to be limited to the use of any particular material.

The stopper 1 is provided with a recess 2 which may extend partly or completely through the stopper, and may be of any desired transverse cross sectional configuration, the recess in the drawing being disclosed as circular in cross section merely for the sake of convenience of illustration.

A similarly shaped socket member 3 is mounted within the recess 2, and is rigidly secured therein by suitable means such, for instance, as by an adhesive. This socket member carries a dipper 4 which in the form illustrated in the drawing is a glass rod, the rod being suitably attached to the socket member as, for instance, by extending into a recess 5 in the socket member, and being secured therein in any suitable manner, such as by frictional engagement or by means of an adhesive.

The material of the socket member is relatively rigid and non-compressible, so that the forces applied to the resilient portion of the stopper are repelled by the socket member and are, therefore, not transmitted to the dipper. It has been found that wood serves admirably as a material for the socket member, but obviously the range of material is wide and the invention is not to be limited to the use of wood. The result of the repelling of these forces by the socket member or sheath 3 is that the dipper will not be subjected to the forces and consequently the possibility of dislocation or fracture will be entirely obviated.

Moreover the location of a relatively rigid socket member within the stopper results in the formation of a core which tends to prevent the breaking of the stopper as it is being extracted from the container.

While I have illustrated a particular embodiment of the invention, I do not wish to be limited to that embodiment as it is obvious that many changes in the details of 5 construction may be made within the scope of the claims.

In the modification shown in Figure 3 the dipper is extended completely through the cork 6, and extends beyond the upper end 10 of the cork as at 7, being secured in the cork by suitable means such as by an adhesive. The purpose of the extension of the portion 15 of the dipper beyond the end of the cork is so that this portion of the dipper may be used as a grip, by means of which the cork may be extracted without injury, such as often occurs when the cork is soaked or soggy, or when it is subjected to the action of a corkscrew.

20 It is of course to be realized that the portion of the dipper which extends into the container in the construction shown in Figure 3 may be omitted, leaving only that portion which is secured within the cork and that portion which extends beyond the end 25 of the cork. This construction will be useful in the instances when it is desirable to have means for extracting the cork and yet unnecessary to have a dipper extending within 30 the container.

In Figure 4 a modification of the construction shown in Figure 3 is disclosed in which the upper portion 8 of the dipper is roughened in order to produce a more effective 35 grip. The dipper in this instance is also provided with an enlarged portion 9 which is adapted to engage the lower end of the cork and prevent any tendency of the dipper rod 40 to pull through the cork. Of course in this case that portion of the dipper rod which is located within the cork may be, if desired, secured to the cork as for instance by an adhesive.

Moreover, if it is desirable to omit the

portion of the dipper which extends into 45 the container from this construction, this may be done leaving only the enlarged portion 9 and that portion which extends through and beyond the cork.

What I claim is:

1. A stopper comprising a tubiform body made from resilient material with a longitudinal bore opening through ends thereof, and a force resisting core entirely filling the bore and permanently fixed within the body 55 from end to end of the same, said core being flush with the ends of the body, and a dipper having one end embedded in the core for a distance less than the length thereof with the engaged end of the dipper completely surrounded snugly by the core.

2. A stopper comprising a tubiform body made from resilient material with a longitudinal bore opening through opposite ends thereof, a force resisting core entirely filling the bore and permanently fixed within the body from end to end of the same, said core being flush with the ends of the body, and a dipper having one end embedded in the core for a distance less than the length thereof with the engaged end of the dipper completely surrounded snugly by the core, said body at its initial engaging end being tapered.

3. A stopper comprising a tubiform body made from resilient material, a force resisting core embedded in said body, and a dipper of fragile material extending from said body and having its end embedded in said core, the engaged end being completely surrounded snugly by the core and entirely out of contact with the resilient material of the body.

In testimony whereof, I have signed my name to this specification this ninth day of December, 1925.

LOUIS J. RUSSELL.
